UNITED STATES PATENT OFFICE.

WILLIAM C. KOMPART, OF BELLAIRE, OHIO.

RESILIENT WHEEL.

1,229,095.

Specification of Letters Patent. Patented June 5, 1917.

Application filed October 25, 1916. Serial No. 127,646.

To all whom it may concern:

Be it known that I, WILLIAM C. KOMPART, a citizen of the United States, residing at Bellaire, in the county of Belmont and State 5 of Ohio, have invented certain new and useful Improvements in Resilient Wheels, of which the following is a specification, reference being had to the accompanying drawings.

10 This invention relates to certain improvements in resilient wheels and has relation more particularly to a wheel of this general character wherein a cushioned hub is employed; and it is an object of the invention 15 to provide a novel and improved device of this general character which serves to substantially eliminate all shocks and jars incident to the travel of the wheel.

The invention consists in the details of 20 construction and in the combination and arrangement of the several parts of my improved wheel whereby certain important advantages are attained and the device is rendered simpler, less expensive and otherwise 25 more convenient and advantageous for use, all as will be hereinafter more fully set forth.

The novel features of the invention will 30 hereinafter be definitely claimed.

35 In order that my invention may be the better understood, I will now proceed to describe the same with reference to the accompanying drawings, wherein—

Figure 1 is a view in side elevation with 40 portions broken away of a wheel constructed in accordance with an embodiment of my invention;

Fig. 2 is a sectional view taken substantially on the line 2—2 of Fig. 1; and

Fig. 3 is a sectional view taken substantially on the line 3—3 of Fig. 1.

As herein embodied, my improved wheel 45 comprises a central disk 1 of wood or other suitable material and which serves as a hub adapted to be mounted upon the spindle S or the like and for which purpose the disk 1 at its axial center is provided with the oppositely directed sleeves 2. Surrounding the disk 1 and bearing against the periphery 50 thereof is a pneumatic or inflatable tube 3.

Concentric to the disk 1 but spaced relatively thereto is an annular member or rim 4 provided with a plurality of equi-distantly spaced and inwardly directed lugs or members 5 substantially semi-circular in form and adapted to frictionally engage the pe-

riphery of the tube 3 hereinbefore referred to and which is clearly shown in Fig. 1 of the accompanying drawings.

Secured to the opposite faces of the disk 60 1 are the metallic plates 6 provided with the radial extensions 7 which overlie the faces of the annular member or rim 4 and have their outer extremities connected by the annular member 8 preferably integrally formed 65 therewith.

Each of the extensions or arms 7 has its inner portion outwardly bowed, as indicated at 9, so that the same may readily bridge the tube 3, while the outer portion of said 70 extension or arm 7 has pressed or otherwise formed therein a socket 10 in which is seated an anti-friction member 11 herein disclosed as a spherical body and which is adapted to contact with the adjacent side 75 plate 12 affixed to the annular member or rim 4. The plate 12 is employed in view of the fact that it is preferred that said annular member or rim 4 be of wood, although I do not wish to be understood as limiting 80 myself to this exact construction.

When the wheel is under load it will be at once self-evident that the annular member or rim 4 is capable of movement relative to the disk 1 and that the shocks or jars incident to the travel of the wheel will be substantially absorbed by the inflated member 3.

In order to hold the annular member or rim 4 against undue rotary movement relative to the disk 1, I find it of advantage to 90 have portions of each of the annular members 8 offset outwardly, as indicated at 14, and as is particularly illustrated in Fig. 3, it will be noted that each of the offset portions 14 bridges a radially disposed rib or 95 flange 15 secured to an adjacent face of the rim or annular member 4 or more particularly the plate 12 secured thereto.

Straddling the rib or flange 15 is a substantially U-shaped member 16, the legs or 100 flanges of which have pressed or otherwise formed therein the sockets 17 in each of which is seated the anti-friction member 18 adapted to ride upon the adjacent face of the flange or rib 15, whereby it will be perceived that the relative movement of the rib or flange 15 and the member 16 will be obtained with a minimum of resistance.

Interposed between and operatively engaged with each of the legs of the member 16 110 and the adjacent end of the offset portion 14, is a coil spring 19 whereby it will be per-

ceived that the member 8 and the annular member or rim 4 are capable of limited cushioned relative movement.

20—20 denote plates secured to the annular member or rim 4 and serve to substantially incase the opposite faces of my improved wheel, said plates 20 being provided at their axial centers with enlarged openings through which the spindle S or the like 10 may be directed. The outer plate 20 has the opening thereof defined by the outstanding annular flange 21 with which is adapted to be detachably engaged the cap 22. It is thought to be self-evident that the plates 15 20 serve to prevent mud or the like from affecting the efficiency of the wheel.

As herein embodied, the periphery of the annular member or rim 4 has suitably affixed thereto a rubber tire T, although this 20 in itself forms no particular part of my invention.

From the foregoing description, it is thought to be obvious that a wheel constructed in accordance with my invention is of 25 an extremely simple and comparatively inexpensive nature and is particularly well adapted for use by reason of the convenience and facility with which it may be assembled, and it will also be obvious that my invention 30 is susceptible of some change and modification without material departure from the

principles and spirit thereof and for this reason I do not wish to be understood as limiting myself to the precise arrangement and formation of the several parts herein 35 shown in carrying out my invention in practice, except as hereinafter claimed.

I claim:

A resilient wheel consisting of a central member, a cushioning member surrounding 40 said central member and in contact with the periphery thereof, an annular member concentric to the central member and spaced relatively thereto and in contact with the cushioning member, annular members carried by the central member and overlying the sides of the first named annular member, each of said last named annular members being provided with an outwardly offset portion, the first named annular member being 45 provided with a radial flange bridged by said offset portion, a member slidably engaged with said flange, and spring means 50 interposed between said slidably member and the opposite ends of the offset portion. 55

In testimony whereof I hereunto affix my signature in the presence of two witnesses.

WILLIAM C. KOMPART.
